Atty.

UNITED STATES PATENT OFFICE.

EDWARD A. GEOGHEGAN, OF HIGHLAND PARK, MICHIGAN, ASSIGNOR OF ONE-HALF TO
WILLIAM MATTHEWS, OF NEW YORK, N. Y.

STEAM-GENERATOR.

1,261,380.

Specification of Letters Patent.

Patented Apr. 2, 1918.

Application filed December 26, 1916. Serial No. 138,900.

To all whom it may concern:

Be it known that I, EDWARD A. GEOGHEGAN, a citizen of the United States, residing at Highland Park, in the county of Wayne 5 and State of Michigan, have invented certain new and useful Improvements in Steam-Generators; and I do hereby declare the following to be a full, clear, and exact description of the invention, such as will enable 10 others skilled in the art to which it appertains to make and use the same, reference being had to the accompanying drawings, and to the letters of reference marked thereon, forming part of this specification.

15 My invention relates to water-tube steam generators, and consists in certain improvements in the construction and operation of steam generators hereinafter described and pointed out.

20 The drawing is an endwise view of a steam generator embodying my invention, installed in a suitable boiler-setting and provided with a convenient system of baffle-walls.

25 In the drawing A indicates a feed-water receiving drum; B indicates a lower or mud-drum; C indicates a water-drum; and D indicates the steam-drum; A' indicates the feed-water supply pipe and B' indicates the 30 blow-off pipe, and D' indicates the steam exit connection.

From the feed-water drum A a bank of down-flow tubes E of relatively small diameter (for example $2\frac{3}{4}$ ") leads to the mud-drum B. From the mud-drum B to the water-drum C is a bank of up-flow tubes F of relatively large diameter (for example $3\frac{1}{4}$ "). From the water-drum C to the steam drum D is a bank of tubes of less diameter (for 40 example 3") and from the steam drum D to the feed-water drum A is a bank of equalizing tubes H of less diameter than the tubes E (for example 2") the function of which is to balance the pressure between the steam-drum D, and the feed-water drum A.

J indicates the back fire-wall of the boiler setting; J' indicates the furnace grates; K indicates the front wall of the boiler setting; K' indicates the rear wall thereof; L indicates the top or cover thereof and L' indicates the smoke exit therefrom. Within this setting I arrange a system of baffle walls to guide the fire gas along and among the tubes of the several banks; an example of which 50 is shown in the drawing as follows: M in-

dicates a baffle above the bank of tubes F from the lower or mud-drum B; and M' indicates a vertical baffle extending from the upper end of the baffle M, part way across the bank of tubes G, so that the fire-gas will 60 flow upwardly under the baffle M among the bank of tubes F and between the vertical baffle M' and the water-drum C, and over the upper edge of the baffle M'.

In front of the feed-water drum A, bank 65 of tubes E, and tubes H is a baffle N, which extends downwardly from the steam-drum D and is provided with a rearward extension N', which extends part way across the bank of tubes E; and above the extension N' 70 is another baffle N² which extends from the rear wall K' of the boiler setting forwardly part way across the bank of tubes E, so that the fire-gas will flow downwardly from the upper bank of tubes G around the extension 75 N' of the baffle N, and among the tubes of the bank E, around the front end of the baffle N², and to the smoke exit L'; also back of the equalizing tubes H, is placed a baffle O.

From the foregoing description of the 80 construction and arrangement of my improved steam generator and setting therefor, it will be seen that the largest tubes F are exposed to the fire-gas at the point of its greatest degree of heat, and that the water 85 flowing therethrough is, by the smaller tubes comprising the upper bank G, divided into smaller columns at a point in the setting where the heat of the fire-gas is less intense; and lastly in the final upward pass of the 90 fire-gas, at the point in the setting where the temperature of the fire-gas is lowest, the water in the bank of tubes E flowing from the feed-water drum into the mud-drum is divided into small columns and will absorb 95 a substantial amount of heat therefrom because of the increased amount of surface exposed to the fire-gas. The equalizing tubes H, being cut off from the fire-gas by means of baffle-walls, do not absorb any heat, so 100 that there will be no upward flow of water therein, and consequently no ebullition of the water in the steam-drum D. In operation the water supplied to the feed-water drum A will flow through tubes E to the 105 mud-drum D, being raised to the steaming point while passing therethrough. From the mud-drum it flows upward through the tubes F to the drum C, from which it enters the upper and smaller tubes G wherein it is 110

J indicates the back fire-wall of the boiler setting; J' indicates the furnace grates; K indicates the front wall of the boiler setting; K' indicates the rear wall thereof; L indicates the top or cover thereof and L' indicates the smoke exit therefrom. Within this setting I arrange a system of baffle walls to guide the fire gas along and among the tubes of the several banks; an example of which 50 is shown in the drawing as follows: M in-

converted into steam, so that little or no water enters the upper or steam drum D. It will thus be seen that there is little or no circulation of water from the steam drum D to the feed-water drum A through the tubes H, and that by reason of the tubes of different sizes I am enabled to convert all the water into steam during its passage from the feed-water drum to the steam-drum D, so that it is not necessary to pass the water a second time through the boiler.

Having thus described the construction and operation of my invention so as to enable others to construct and utilize the same, I do not desire to be limited to the exact form and dimensions shown and described, as many alterations can be made therein without departing from the scope of my invention; but what I claim as new and desire to secure by Letters-Patent is:—

In a steam generator, a boiler setting comprising substantially front, rear, side walls,

cover, and fire-back wall, a mud drum supported on said fire-wall, a water drum supported adjacent to the upper part of said front wall, a steam liberating drum supported adjacent to said cover and above said mud drum, a feed water receiving drum between said mud drum and said steam liberating drum, a series of down-flow equalizing tubes connecting said steam liberating and said feed water drums, a series of relatively small down-flow water tubes between said feed-water and mud drums, a series of up-flow water tubes of relatively large diameter between said mud drum and water drums and immediately over the furnace grates, and a series of up-flow water tubes of intermediate diameter between said water and steam liberating drums immediately under said cover, substantially as described.

In testimony whereof I affix my signature.

EDWARD A. GEOGHEGAN.
